UNITED STATES PATENT OFFICE.

HARRY CROSS HUBBELL, OF JERSEY CITY, NEW JERSEY.

INCANDESCENT ELECTRIC LAMP.

No. 832,730.

Specification of Letters Patent.

Patented Oct. 9, 1906.

Application filed January 26, 1905. Serial No. 242,769.

To all whom it may concern:

Be it known that I, HARRY CROSS HUBBELL, a citizen of the United States, residing at Jersey City, in the county of Hudson and State of New Jersey, have invented new and useful Improvements in Incandescent Electric Lamps, of which the following is a specification.

This invention relates to incandescent electric lamps, especially for that type known as "portable" or "mine" lamps; and it has for its principal object the production of an illuminating-lamp in which a festoon-bulb is held supported upon two spring-wires in such a manner that should the bulb be broken the two supported ends thereof would drop off the spring-wires in order that a connection could not readily be made between the two ends of the platinum points. With lamps of this type it has been possible, unless special provision has been made to prevent it, to connect the two platinum points by placing a knife-blade or other device between them until the wires are heated to a dangerous incandescence.

One of the objects of this invention is to overcome this defect, more especially in a lamp in which a reflected light is produced having no shadows cast which will interfere with the effectiveness of the lamp.

These and other objects are attained by means of the construction illustrated in the accompanying drawings, in which—

Figure 1 is a front elevation of a lamp made in accordance with my present invention. Fig. 2 is a similar view and showing the positions assumed by the ends of the bulb when the same is broken. Fig. 3 is a perspective view of a portion of the lamp with the bulb removed. Fig. 4 is a side view of the bulb removed from the lamp. Fig. 5 is a face view of the illuminating portion of the lamp and showing a temporary or auxiliary bulb in place for use.

Referring to the drawings for a more particular description of the invention, the numeral 1 designates a lamp casing or body, which may be of any suitable structure or configuration, and 2 is a glass globe secured to the lamp-body. The numeral 3 denotes a white or enameled reflector, and 4 are two binding-screws which secure in place the two fine-wire supports 5, 5, said supports each comprising a base-loop 6, through which the

binding-screw 4 passes to hold said support 5 in place. Extending outward from the loop 6 is a supporting-arm 7, the end of which terminates in a finger 8, which may be suitably extended at an angle to the arm 7 for a purpose which will presently appear.

The festoon-bulb 9 has extended through its opposite ends a platinum terminal 10, the outer ends of said wires being bent into loops 11, designed to engage and be supported from the fingers 8 on the supporting-arms 7. A filament may be connected to the platinum wires 10 inside the bulb 9.

The lamp is especially designed to be connected to a vertical support, and since the fingers 8 are slightly inclined the loops 11 are held in place normally by the relative inclination of said fingers, the loops b serving as stops to prevent the loops 11 from passing too far back.

Should the bulb 9 become broken, the opposite ends of the same would fall to the positions indicated in Fig. 2, the loops 11 turning upon the fingers 8 or dropping off at the terminal ends. Under these conditions it would be difficult, if not practically impossible, to so connect the platinum points 10 to cause the wires to become heated.

As shown in Fig. 3, the face of the illuminating portion of the lamp is provided with an opening 12, adapted to receive a charging-plug a.

In gaseous mines and other locations where it would be dangerous to complete a circuit between the two points 10, either by accident or design of some ignorant person, a safety device such as that described in the foregoing specification has been found particularly desirable. When bulbs are broken and the wires are heated at the ends, explosions are likely to occur.

Various changes in form and proportions may be made without departing from the spirit of my invention.

Having thus described my invention, what I claim, and desire to secure by Letters Patent, is—

1. In an electric lamp, an incandescent bulb having platinum terminals extending outside the bulb and formed into loops, in combination with inclined wire fingers passing through the loops to support the bulb and permit the latter to fall from said fingers when broken.

2. An incandescent electric - light bulb having its platinum-wire terminal extended through the sides of the bulb and terminating in loops, and wire fingers extended through the loops for supporting the bulb in its normal position and permitting it to drop off the fingers when broken, said fingers normally

inclined and having a tendency to spring laterally.

HARRY CROSS HUBBELL.
